UNITED STATES PATENT OFFICE.

FRED J. FISHER, OF DETROIT, MICHIGAN.

PROCESS FOR BENDING WOOD.

1,016,684.

Specification of Letters Patent.

Patented Feb. 6, 1912.

Application filed January 10, 1910. Serial No. 537,121.

To all whom it may concern:

Be it known that I, FRED J. FISHER, a citizen of the United States, residing at Detroit, county of Wayne, State of Michigan, have invented a certain new and useful Improvement in Processes for Bending Wood, and declare the following to be a full, clear, and exact description of the same, such as will enable others skilled in the art to which it pertains to make and use the same, reference being had to the accompanying drawings, which form a part of this specification.

This invention relates to the art of wood bending, and has for its object an improved process of producing companion rails of bent wood.

In carrying out the process I employ a strap which has as a characteristic feature the ability to bend in two directions. A strap having this characteristic is shown and described in my Patent No. 966,678.

I produce companion rails by placing two rails or bars of wood side by side in the bending former and use the outer rail as a strap which acts in conjunction with the flexible strap and form to compel the inner rail to assume the proper curvature, and use the inner rail to compel the outer rail to assume the proper curvature, each serves as a form for the other. After the bending is completed the two lie closely together.

In the drawings:—Figure 1, is a plan

view of the two rails under the bending strap. Fig. 2, is a perspective of a pair of rails bent to form.

The outer rail 1 engages closely around the inner rail 2. Compound curves are produced by means of the two way flexible strap 3. The outer rail 1 serves as a strap to protect the inner rail 2 from breaking and splitting around the curve 4, and the two rails thus bent engage in intimate relation throughout their extent.

What I claim is:—

The process of bending rails intended for companion use at angles in which the fiber is placed under relatively great tearing stresses, which comprises arranging the rails so that adjacent faces register, placing them in an insheathing strap, affording a bending stress in the plane common to all the rails, the said strap protecting and shaping the outlying faces of the rails under stress and the abutting faces of the rails, protecting the fibers of one another and shaping one another intimately for said companion usage, substantially as described.

In testimony whereof, I sign this specification in the presence of two witnesses.

FRED J. FISHER.
